END LINK FOR A WATCH BAND

Stanley Meyerson, 1350 Ocean Parkway,
Brooklyn 30, N.Y.

Filed Mar. 12, 1963, Ser. No. 73,941

Term of patent 14 years

(Cl. D45—4)

FIG. 1

FIG. 2

FIG. 3

FIG. 4

FIG. 5

FIG. 1 is a top plan view of an end link for a watch band showing my new design;

FIG. 2 is a longitudinal section taken on line 2—2 of FIG. 1;

FIG. 3 is an enlarged transverse section taken on line 3—3 of FIG. 1; and

FIG. 4 is a transverse section taken on line 4—4 of FIG. 1;

FIG. 5 is an end elevational view looking in the direction of line 5—5 of FIG. 1.

I claim:

The ornamental design for an end link for a watch band, as shown.
